US00D869352S

(12) **United States Design Patent** (10) Patent No.: **US D869,352 S**
Duncan et al. (45) Date of Patent: **** Dec. 10, 2019**

(54) **GRILLE UNIT**

(71) Applicants: **Jonathan S. Duncan**, Seattle, WA (US); **Amanda Koh**, Kenmore, WA (US); **Peter Vurpillat**, Seattle, WA (US); **Chris Small**, Seattle, WA (US); **John Jackson**, Sammamish, WA (US); **Rebecca Kern**, Kent, WA (US)

(72) Inventors: **Jonathan S. Duncan**, Seattle, WA (US); **Amanda Koh**, Kenmore, WA (US); **Peter Vurpillat**, Seattle, WA (US); **Chris Small**, Seattle, WA (US); **John Jackson**, Sammamish, WA (US); **Rebecca Kern**, Kent, WA (US)

(73) Assignee: **PACCAR INC**, Bellevue, WA (US)

(**) Term: **15 Years**

(21) Appl. No.: **29/644,084**

(22) Filed: **Apr. 13, 2018**

(51) LOC (12) Cl. **12-16**

(52) U.S. Cl.

USPC **D12/163**

(57) **CLAIM**

The ornamental design for a grille unit, as shown and described.

DESCRIPTION

FIG. 1 is a front and right side perspective view of a grille unit showing our new design;

FIG. 2 is a front elevational view thereof;

FIG. 3 is a top plan view thereof;

FIG. 4 is a right side elevational view thereof; and,

FIG. 5 is a left side elevational view thereof.

The broken lines shown throughout the drawing views are for environmental and illustrative purposes and form no part of the claimed design.

1 Claim, 3 Drawing Sheets
